KEYBOARD FOR POWER-DRIVEN WRITING MACHINES

Oscar J. Sundstrand, Bridgeport, Conn., assignor to Underwood Elliott Fisher Company, New York, N. Y., a corporation of Delaware

Application December 30, 1936, Serial No. 118,182

3 Claims. (Cl. 197—98)

This invention particularly concerns typewriters employing, in order to ease the labor of the typist and improve production, type actions that are operated by power driven mechanism at 5 operation of the typing keys.

The invention is herein explained with reference to a typewriter, of the Elliott Fisher class, adapted to employ a continuously rotating power driven universal shaft to which the type actions 10 are selectively connectable through operation of the type keys, it being understood that upon its being connected to such shaft, the type action is power operated by the shaft to print.

In prior constructions, the keys are usually 15 horizontal at their tops and are arranged in transverse rows or banks one behind the other, and the banks are definitely stepped one above the other for avoiding interference of the typist's finger, while said finger is engaged in depressing 20 a key, with the next higher or lower key bank.

Each type action may have a connector individually movable, through operation of a corresponding type key, to connect said type action to the power shaft.

In a machine employing power operated type 25 action mechanism, the typist experiences ease in manipulating the keys at a faster rate than in a machine in which the type actions are driven in printing strokes by the force of the typist's fingers. This is due, first, to the fact that in the power operated machine, the typist's fingers do not exert a type driving force or pressure but, on the contrary, simply serve to move the very 30 lightly resistant connectors, and it is further due to the fact that the extent of key stroke employed 35 to move a connector is much less than that necessary and usually employed to drive the type action through the stroke of the finger upon the key.

However, considering the connectors and their type actions apart from the keys, it is demonstrably possible to operate properly said connectors and type actions themselves at an even faster rate of successive operations than the rate at 40 which the speediest typist is accustomed to operate the keys of a power-action typewriter.

Thus, in a power operated type action mechanism, the typing speed that is attainable by the typist is limited not by the connector and type 45 action mechanism itself, but it is only limited by the ease and rapidity with which the keys can be manipulated by the typist.

An object of the invention is to provide for 50 utilizing more fully the inherent capability of the power driven type actions for speedily suc-

cessive operations. To this end the invention aims to surmount to a material degree the limitation to speedy typing such as arises from the conventional arrangement of the usual typewriter keyboard. Therefore, the invention proposes for the power driven type action mechanism a keyboard improvement that makes it materially easier to manipulate the keys faster than in the ordinary keyboard.

Another object is to retain, in the improved 10 keyboard, a sufficient stepping of the key banks for the purpose, as aforesaid, of avoiding interference.

Another object is to employ the improved keyboard arrangement in conjunction with type key 15 presenting levers that according to preferred practice, extend rearwardly from the several banks of keys to a common fulcrum axis behind the keyboard.

I attain these objects, and gain therefrom unexpected advantages, by employing power-type-action controlling type key levers and in association therewith a keyboard having stepped banks of keys, but having the finger engaged tops of the keys pitched downwardly at an angle from back to front as compared with the heretofore employed horizontal postures of the key tops.

Thus, the improved power-type-action, controlling keyboard considered generally may be regarded, in respect of the key tops, as being pitched or sloped downwardly from back to front and substantially as having the banks stepped perpendicularly to the pitch. The angle of pitch may be, say, 10° from the horizontal.

The space key bar usually provided at the 35 front of the keyboard may have its top finger surface pitched downwardly consonantly with the general pitch of the key tops.

With my improved pitched key-top, power-type-action controlling keyboard, the typist definitely experiences, in respect of rapid typing, greater ease in rapidly moving the fingers laterally over the keyboard, and in rapidly reaching, that is, ascending or descending, from bank to bank, and is thus definitely enabled to operate 40 the keys at a materially faster rate for utilizing more fully the capability of the power mechanism for operating the types in speedy succession.

One aim in providing power-operated type action mechanism in typewriters is to ease the labor of the typist's arms, wrists and fingers in typing in that the key strokes in power typing are usually shallow in depth and each stroke in itself requires little effort. Thus, as compared 55

within the practice for manually operable or finger-driven types, the arm, wrist and finger movements required in manipulating the keys in power typing are much less and are executed with less force than in hand typing, and, therefore, in power typing the typist's arms, wrists and fingers are more relaxed and are much less apt to become fatigued. My improved sloping keyboard conduces even more and thus materially to favoring and obtaining relaxation of the typist's arms, wrists and fingers and, therefore, the keys may be operated faster or with less effort than in the conventional horizontal-keyboard, and it follows that there is gained fuller benefit of the capability of the power type actions themselves for operation in rapid succession, and fuller realization of the aim in using power-type-actions.

Another advantage resulting from thus sloping or pitching the key-tops is that the rise of the keyboard from bank to bank appears to be reduced vertically and the key tops are more nearly perpendicular to the typist's usual line of vision.

The downwardly and forwardly inclined keys may be fixed directly on key levers that extend at different lengths, according to the different key banks, from a preferably common fulcrum axis behind the keyboard. It is feasible, in using power operated type actions controlled by such key levers, to employ means limiting the strokes of the key levers to such degree that the downward and forward inclination or pitch of the finger engaged key top planes is not materially altered during the operative range of movement of the key levers about their pivots. Thus the typist's fingers sense no excessive pitch of the key top plane at the bottom of the key stroke and this conduces materially to the typist's sense of security in avoiding any slipping of the fingers off the key tops at the bottom of the key strokes, and hence facilitates rapid manipulation of the keyboard.

So far as I am aware, it is entirely novel in concept and spirit to combine a definitely stepped keyboard, but with the key tops sloping downwardly toward the front, with a power operated type action mechanism, and it is further entirely novel to thus achieve, through the resulting enabling of faster key operation by the typist's fingers, a fuller and more advantageous use of the capability inherent in the power operable type actions themselves for their successive operations at a speedy rate.

Other features and advantages will hereinafter appear.

In the drawings.

Figure 1 is a perspective view of an Elliott-Fisher writing machine, equipped with my improved keyboard;

Figure 2 is a sectional view through the keyboard and its associated parts, showing the arrangement of the keys in banks or tiers, and the key and type bar action, and

Figure 3 is a fragmentary top plan view.

The Elliott-Fisher key carriage 10 is supported to travel in letter spacing direction and return, on tracks 11 forming part of a line space frame 12 which, in turn, is supported for movement in line spacing direction on rails (not shown) suitably mounted on a stand or base.

The horizontal platen 13 is located below the key carriage.

Suitable letter and line spacing mechanisms, not shown, are provided to advance the key carriage over the platen in letter spacing direction,

and to shift the line space frame 12 with its key carriage 10 in line spacing direction.

Reference may be made to patents to Foothrap, No. 1,203,519, October 31, 1916, and 1,904,127, April 18, 1933, for a more complete description of the foregoing and other mechanisms used in the Elliott-Fisher machine herein illustrated.

The lower ends of the side walls of the key carriage frame are projected forwardly, as at 14, the outer ends of such forward projections being connected by a cross bar 15, to form a hollow frame or cavity to embrace the keyboard.

The keyboard per se comprises the forward ends of the key levers 19^b, there being a separate key for each letter of the alphabet and each numeral, together with certain punctuation marks, the ordinary keyboard including some 40 to 44 keys.

In the present instance, these key levers project forwardly through guide slots 21 formed in the vertical flange of a cover plate 22 extending over the top of the key carriage frame, the rear ends of the key levers being pivoted in alinement on a cross rod 20 mounted at its opposite ends in the side walls of the key carriage frame, and lying just behind the vertical slotted flange.

Limiting arms 19^a project upwardly from each key lever, through slots 23 in the cover plate, the upper ends of the arms entering their respective limiting slots 24 formed in a guide plate 25 extending between and supported at the upper ends of vertical side brackets 26 mounted on the opposite ends of the cover plate 22.

These limiting slots are graduated in length in correspondence with the lengths of the key levers 19^b, the arms 19^a of the longest key levers entering the shortest slots in the guide plate, the arms 19^a of the next shortest key levers, entering the next longest limiting slots, and so on, to offset the greater arcs of travel of the longer levers and equalize the extents of depression of the keys.

Springs 27 connected to the individual key lever arms 19^a normally hold the latter against the rear walls of the slots 24 in the guide plate, and maintain the key levers 19^b in their normal elevated positions.

In that form of mechanism herein shown, each key lever arm 19^a is provided with a pair of rearwardly extending jaws 29 to form an open ended seat for a stud 30 projecting laterally from the forward end of a drag link 28 which extends over a continuously rotating, fluted shaft 130 driven by motor power in any convenient manner, as that set forth in my co-pending U. S. application for patent, filed December 5, 1936, Serial No. 114,416. A spring 31 connected at its opposite ends to the key lever arm and to the drag link, respectively, normally holds the stud 30 of its drag link at the forward closed end of the seat 29, and constitutes a yielding connection between the key lever arm 19^a and its drag link 28. The rear end of each drag link is hooked to take over a lateral pin 32 carried by a thrust link 40 individual to each key lever and forming part of a toggle mechanism which also includes a radius arm 75 and a connecting link 70.

The radius arms of the several toggle mechanisms, there being one such toggle mechanism for each key lever 19^b, as is well understood, are individually journaled in a common horizontal line, as on the rod 76 suitably held in a slotted cradle 71 supported by the upper face of the cover plate 22, the thrust link 40 extending downwardly past the toothed drive shaft 130, and being pivoted at its lower end, as at 80, to one side of the 75

radius arm 75. The upper end of the connecting link 78 is pivoted to the opposite side of the radius arm, at 74.

5 A disengaging spring 85 anchored to the associated key lever arm 19^b and to a forwardly projecting toe 86 at the lower end of the thrust link 48, normally holds the toggle mechanism in flexed position, with the thrust link 48 alined against a rearwardly inclined arresting plate 84 10 extending between and supported by the side brackets 26.

The connecting links 78 depend through slots 73 in the cover plate 22, the lower end of each connecting link 78 being pivoted to its individual intermediate lever 58, at 71. Each intermediate lever is journaled at its rear end on a cross rod 59 extending between the side walls of the key carriage frame, the intermediate lever projecting forwardly, and being guided at its front end in 20 a slot 62 formed in the front wall of the key carriage casing. A spring 81 connected to the intermediate lever 58 operates to yieldingly hold the lever and its connected parts in raised position.

25 An extensible link 57 depending from the intermediate lever 58, connects the latter with one end of a sub-lever 55 pivoted on a post 56 projecting upwardly from the recessed deck 41 customarily provided in machines of the Elliott-30 Fisher type and forming part of the key carriage 10. A second link 54 connects the remaining end of the sub-lever 55 with an elbow lever 52 pivoted by one arm, at 52^a, to a post 53 depending from the deck 41 adjacent the recess therein, and 35 a third link 51 connects the lower arm of the elbow lever 52 with the tail of the appropriate type bar 45 pivoted at 46 to a bracket 44 fastened to the arcuate type bar ring or segment 42 suspended below the deck 41 and forming part of the key carriage. A type 47 is mounted in the free end of each type bar.

40 A spring 48 connected to the type bar 45 yieldingly retains the type bar in, and returns it to its normal vertical position, as shown, wherein the free end of the type bar rests against a buffer ring 49.

45 A pawl 81 pivoted at 82 on each of the thrust links 48 at a point thereon opposite the continuously rotating drive member 130, when the thrust link is in its normal elevated position, is provided with a lateral extension (indicated in dotted lines) to contact a shoulder 98 formed on the thrust link.

50 It will be understood that the above description of the single type bar action applies to the several type actions associated with their respective key levers 19^b.

55 Any key lever 19^b when manually depressed will rock counter-clockwise (Fig. 2) on its pivot 20 against the tension of its restoring spring 27, tensioning its yielding link 31 to advance the associated drag link 28, the latter, because of its hooked end, operating to rock its thrust link 40 forwardly on its pivot 80, to not only engage 60 the pawl 81 with the toothed drive member 130, but also to straighten the toggle mechanism.

65 The drive member 130, when engaged by the pawl 81, drives the alined toggle links 48, 70 downwardly, to rock downward the appropriate intermediate lever 58 and through the hereinbefore described linkage, effect an impact of the type 47 on the type bar 45 against the work on the platen 13.

75 The arrangement of the parts is such that the pawl 81 disengages itself from the drive member

130 just prior to the contact of the type with the work on the platen 13, whereupon, after the printing has occurred, the type bar spring 48, intermediate lever spring 61 and thrust link spring 85 operate to return the parts to normal, and when pressure on the key lever 19 is relieved, the latter with its drag link 28 are restored to normal by the spring 27. The spring 85 also flexes the toggle links 48 and 78 which have been alined or straightened by the key 19^b.

10 The foregoing description has been introduced to show the reason for an elevated keyboard in a downstrike writing machine, and to disclose one form of mechanism to which the present invention, now to be explained, is particularly applicable.

Sloping keyboard

15 In machines of the foregoing type, it will be observed that, because of the height of the keyboard, the operator sitting on a chair of the usual height is at a disadvantage, as his forearms must be inclined upwardly at an awkward angle, which soon becomes tiresome and fatiguing, and prevents speedy operation of the machine.

20 These disadvantages are increased in former machines by the necessity for depressing the keys by pressure vertically applied to horizontal key tops.

25 It is true that when the key levers extend from a pivoted point at the rear of the machine, the prejudicial results may be slightly less because of the wider arc of travel of the outer free end of the key lever, though still present in some degree, but in instances where shorter key levers are provided, the arc of travel described by the forward end of the key and to be followed by the operator's finger, is considerably sharper, resulting in materially slowing the speed at which the machine can be operated.

30 To eliminate the foregoing objections, I have devised a novel keyboard wherein, while still retaining the application of pressure to the key levers in a direction substantially at right angles thereto, I arrange that the direction of movement of the operator's fingers in applying such pressure to the keys shall be at a less angle to the horizontal than the vertical blow necessitated by the usual design of keyboard now in commercial use.

35 Describing the application of my invention to a machine equipped with short key levers, that is, one wherein the key levers are fulcrumed near the front of the machine, as in the accompanying drawings, it will be noted that each of the key levers of the uppermost bank of keys is provided with a horizontal reach 19^b extending forwardly from the fulcrum 28 to a point slightly past the slotted guides 21, after which the key lever is continued at a sharp downward inclination of say, 40 45 degrees more or less, the outer end of the downwardly inclined reach terminating in an upwardly extending, forwardly tilted key stem 19^c lying at an angle of substantially 10 degrees from the vertical.

45 The key levers of the next or second highest bank of keys, have the same horizontal reach identical with the horizontal portions of the keys of the highest bank, and parallel therewith, the key levers of the second highest bank being continued from the outer ends of the horizontal reaches in a steep downward incline exactly as the key levers of the highest bank, and parallel therewith, but the steep inclines of the key levers appropriate to the second highest bank are pro- 50 55 60 65 70 75 80 85 90 95 100

longed downwardly beyond the key stems 18° of the highest bank, for a sufficient distance to space the keys of the second highest bank in advance of the keys of the highest bank so that 5 the operator's fingers will clear either bank of keys when operating the other.

Key stems 18° inclined at similar angles to the vertical, project upwardly and tilt forwardly from the lower ends of the steeply inclined reaches of 10 the key levers of the second highest bank, such key stems being slightly longer than the key stems 18° on the key levers of the highest bank, to compensate for the greater depth to which the steeply inclined parts of the key levers of the 15 second highest bank extend, whereby to locate the upper ends of the key stems a step downward, say about three-eighths of an inch, from the upper ends of the key stems of the highest bank, so as to enable the operator's fingers to clear the 20 second highest bank when depressing keys of the highest bank.

The third highest bank of key levers is in substantial parallelism with the levers of the second highest set, but instead of prolonging the steeply 25 inclined portions of the key levers to a greater depth than the key levers of the next higher bank, the extended ends of the key levers of the third highest bank are brought forwardly in flattened arcs, from the free ends of which project 30 key stems 18° shorter than the key stems of the next higher bank, such shorter key stems extending upwardly and forwardly at substantially the same angle as do the key stems 18° and 18° of the higher banks.

35 The arcuate forward extensions of the key levers of the third highest bank serve to space their key stems 18° the requisite distance in advance of the key stems of the next higher bank, and the provision of shorter key stems serves to 40 locate the key tops thereof in lower stepped relation to the key tops 18 of the next higher bank, to form a clearance when the keys of said next higher bank are depressed.

The key levers of the lowest or fourth bank are 45 similar to the keys of the third or next higher bank, except that the flattened arcuate extensions are longer and nearly straight, to space the key stems in advance of those of the third highest bank, and the forwardly tilted key stems 50 18° are very short to effect the step arrangement of the keyboard for the purposes above explained.

Key caps or tops 18 are mounted on the upper ends of the tilted key stems, the contact faces of the key caps assuming a tilt or inclination of, 55 say, about 10 degrees to the horizontal, and lying at right angles to their key stems.

By this combined arrangement of sloping key levers, inclined key stems and slanted key caps, I have contrived a new keyboard for power-driven 60 typewriting machines which eliminates fatigue, enables a speedier operation, and affords a characteristically different touch and operation.

It will be noted that the contact faces of the key caps 18 of the keyboard lie in stepped rows, 65 the key caps of each row lying in their own inclined plane, and the planes of inclination of the several rows being parallel, one above the other.

To further carry out the inclined appearance of the keyboard, the space bar 150 located in advance of the lowest or front row of keys, is mounted on its supporting levers 151 at the same angular degree as are the keys of the several banks, so that the plane of inclination of the space bar parallels and lies below the successive 70 parallel planes of inclination of the stepped rows 75

of keys, to facilitate depression of the space bar and render uniform the depression of the keys and space bar.

It will be obvious, that in a power operated type action mechanism of the kind described, comparatively shallow strokes of the type keys may suffice to throw a connector, such as the pawl 81, into engagement with the power shaft, such as 15 130. Thus, the key lever stroke-limiting means, namely, the key lever arms 19° and the cooperating slots 24 in plate 25 may limit the key lever strokes to such degree that the inclination of the keys 18 will not be materially altered during the operative range of movement of the key levers about their pivot rod 20. 15

Because of the light pressure required to depress the keys of this machine sufficiently to engage the type bar actions with the power-drive element, a staccato touch or blow such as is necessary for the proper operation of a key-actuated type action, is wholly obviated, and hence I have been able to provide a sloping stepped keyboard which can be "played" with a legato touch in much the same manner as a piano. 20

In consequence, the operator may hold his 25 fingers in approximate alinement with his hands which need be inclined upwardly at a slight angle only to the horizontal, similar to the angular plane of the keyboard, to enable the operator by a mere forward and backward movement of his 30 arms, to cover the entire keyboard area, and by a slight rocking of the fingers at the knuckles, to depress the keys.

Retention of the stepped arrangement is necessary to afford a clearance between the operator's fingers and the row of keys next in advance of the keys depressed, but such stepped arrangement instead of being vertical, is inclined, which is possible only because in power typewriting machines it is unnecessary to drive the type actions 40 downwardly to effect printing. 45

What is claimed as new, is:

1. A writing machine, the key levers of which are of varying lengths arranged in progressively higher stepped banks from front to rear; upwardly projecting forwardly inclined key stems on the respective key levers; key caps mounted on the stems at substantial right angles thereto, to lie in progressively stepped, inclined, parallel planes; arms on the key levers; and a limiting plate having slots of varying lengths graduated in correspondence with the lengths of the key levers, and entered by the arms of the key levers, the arms of the respectively longer key levers embraced by the respectively shorter slots. 55

2. In a typewriter, a system of type actions, a system of pivoted type key levers by means of which said type actions are operated, said key levers having fixed thereon keys arranged in transverse rows or banks constituting a keyboard in which said banks are arranged one behind another and are definitely stepped, in different planes at the finger-engageable key tops, one above the other, said key top planes having a downward pitch from rear to front for easing the reaching of the typist's fingers from bank to bank and for easing the effort of said fingers in depressing said keys, and means limiting the strokes of said key levers to such degree that the pitch of said planes will not be materially altered 65 during the operative range of movement of said type key levers about their pivots. 70

3. The combination, in a typewriting machine; of means forming a fulcrum axis; a plurality of type key levers of varying lengths pivoted on and 75

extending forwardly from said axis; each key lever provided with an upwardly extending key stem, the key stems being graduated in height to form rows or banks arranged in a succession 5 of progressively higher steps from front to rear; a key cap fixed on each key stem, arranged with its top in a forwardly inclined plane, the inclined key cap tops of the respective banks of keys being in different planes successively higher from front

to rear, whereby to enable the hands of the operator to crawl back and forth over the keyboard and to reach from bank to bank with ease; and means limiting the strokes of said key levers to such degree that the inclination of said key-caps will not be materially altered during the operative range of movement of said type key levers about said axis. 5

OSCAR J. SUNDSTRAND.
